Primary Examiner — Catherine S Posthauer*Assistant Examiner* — Joan E. Diehl(74) *Attorney, Agent, or Firm* — AVEK IP, LLC; William B. Kircher(57) **CLAIM**

The ornamental design for a carton for frozen dessert, as shown and described.

DESCRIPTION

FIG. 1 is a perspective view of a carton for frozen dessert in a flat, unassembled position, showing our new design:

FIG. 2 is a top end elevational view thereof;

FIG. 3 is front elevation view thereof;

FIG. 4 is a bottom elevational view thereof; and

FIG. 5 is a side elevation view thereof; and,

FIG. 6 is as back plan view thereof.

The broken lines are shown for the purpose of illustrating parts of the article that form no part of the claimed design.

1 Claim, 3 Drawing Sheets
